US0D1112566S

(12) **United States Design Patent** (10) **Patent No.:** **US D1,112,566 S**
(45) **Date of Patent:** **** Feb. 10, 2026**

(54) **SWIM FIN**

(71) Applicants: **FuZhen exercise items Co., Ltd.**,
Taichung (TW); **Yu-Chi Chao**,
Taichung (TW)

(72) Inventors: **Yu-Chi Chao**, Taichung (TW); **Yi Huang**, Taoyuan (TW)

(73) Assignees: **FuZhen exercise items Co., Ltd.**,
Taichung (TW); **Yu-Chi Chao**,
Taichung (TW)

(**) Term: **15 Years**

(21) Appl. No.: **29/942,069**

(22) Filed: **May 14, 2024**

(30) **Foreign Application Priority Data**

Jan. 22, 2024 (TW) 113300330

(51) LOC (15) Cl. **21-02**

(52) U.S. Cl.

USPC **D21/806**
